CHRISTMAS TREE STAND

Joseph A. Sparenga, Cleveland, Ohio

Application April 20, 1950, Serial No. 9,374

Term of patent 7 years

(Cl. D35—3)

To all whom it may concern:

Be it known that I, Joseph A. Sparenga, a citizen of the United States, residing at 3476 West 62nd Street, Cleveland, county of Cuyahoga, state of Ohio, have invented a new, original and ornamental Design for a Christmas Tree Stand, of which the following is a specification, reference being had to the accompanying drawing, forming a part thereof, and in which the figure is a perspective view of a Christmas tree stand showing my new design.

The side of the stand opposite the side shown is similar in appearance and the back is plain.

I claim:

The ornamental design for a Christmas tree stand, as shown and described.

JOSEPH A. SPARENGA.
